ADJUSTABLE LOSS PARALLEL-T NETWORK

Herbert W. Augustadt, West New Brighton, N. Y.,
assignor to Bell Telephone Laboratories, Incorporated, New York, N. Y., a corporation of New York

Application May 29, 1945, Serial No. 596,478

15 Claims. (Cl. 178—44)

1

This invention relates to wave transmission networks and more particularly to networks having adjustable transmission characteristics.

The object of the invention is to adjust the magnitude of the maximum transmission loss in a wave transmission network without changing the frequency at which the maximum occurs.

In accordance with the present invention there is provided a wave transmission network having a peak of transmission loss the height of which may be adjusted without changing its frequency. The network comprises two T's, ordinarily symmetrical, connected in parallel, a resistance bridging the T's and a second resistance connected in common with the shunt branches of the T's. One of the T's comprises two series resistances and an interposed shunt reactance and the other comprises two series reactances and an interposed shunt resistance. The reactances, which are of the same sign, and the resistances forming the T's are proportioned to provide maximum transmission loss at a preassigned frequency and the bridging and common shunt resistances are proportioned to adjust the magnitude of this maximum without changing the frequency. To facilitate adjustment these latter resistances may be made variable.

The nature of the invention will be more fully understood from the following detailed description and by reference to the accompanying drawing, in which like reference characters refer to similar or corresponding parts and in which:

Fig. 1 is a schematic circuit of a wave transmission network in accordance with the invention; and

Fig. 2 shows typical transmission loss characteristics obtainable at various pairs of settings of the variable resistors.

As shown in Fig. 1 the network comprises two T's, ordinarily of symmetrical configuration, connected in parallel between the points 3, 4 and 5. One of the T's comprises two series resistances each of value R_1 and an interposed shunt reactance. The other T comprises two series reactances and an interposed shunt resistance of value R_2 .

In order to provide a transmission characteristic having its maximum loss at a preassigned frequency f_0 the shunt reactance $\pm jX_1$ and the series reactance $\pm jX_2$ must be of the same sign and have the relationship

$$X_2 = 4KX_1 \quad (1)$$

where

$$K = \frac{R_2}{R_1} \quad (2)$$

If the shunt reactance is constituted by a capacitance of value C_1 and each of the series reactances by a capacitance of value C_2 , as shown

2

in Fig. 1, it follows from Equation 1 that the capacitances will have the relationship

$$C_1 = 4KC_2 \quad (3)$$

In this case the frequency f_0 is given by the expression

$$f_0 = \frac{1}{\pi R_1 \sqrt{2C_1 C_2}} \quad (4)$$

The design relationships involved in this portion of the network, when the reactances are constituted by capacitances, are discussed in more detail in my prior United States Patent 2,106,785, issued February 1, 1938.

In order to provide means for adjusting the magnitude of the maximum loss without changing the frequency f_0 at which it occurs, a resistance of value R_x is connected between the points 3 and 4 to bridge the T's and a second resistance of value R_y is connected at one end of the point 5, to form a common impedance in the shunt branches of the T's. The points 3 and 4 are connected, respectively, to an input terminal 6 and the corresponding output terminal 7, and the other end of the resistance R_y is connected to the remaining input terminal 8 and the output terminal 9. A suitable source of alternating electromotive force may be connected to the terminals 6 and 8 and a suitable load impedance to the terminals 7 and 9.

In order not to change the frequency f_0 the product of the resistances R_x and R_y must be equal to a constant which depends upon R_1 and R_2 and may be expressed as

$$R_x R_y = \frac{2R_1^2 R_2}{R_1 + 2R_2} \quad (5)$$

To facilitate the adjustment of the loss peak the resistances R_x and R_y may be made variable, as indicated by the arrows, and for convenience in maintaining the required relationship they may be arranged for unitary control, as indicated by the broken line 10.

The maximum transfer constant θ_{max} in nepers, at the frequency f_0 , for the network is given by the expression

$$\theta_{max} = 2 \tanh^{-1} \sqrt{\frac{1+2K}{1+2K+8Ka(1+a)}} \quad (6)$$

where

$$a = \frac{R_1}{R_x} \quad (7)$$

Fig. 2 shows typical transmission loss characteristics obtainable with the network of Fig. 1 when operating between load impedances each equal to R_1 . The ordinates are decibels and the abscissas cycles per second, on a logarithmic scale. Curve D is for a certain value of R_x , curve E for a small value, and curve F for a still smaller value.

Of course it is to be understood that an infinite

family of curves similar to those shown may be obtained by properly choosing the values of R_x and R_y . As R_x is decreased, R_y is increased, and vice versa, to maintain the product constant, as given by Equation 5. The frequency f_0 of maximum loss θ_{max} is 60 cycles and it will be noted that this frequency does not change as the magnitude of the maximum loss is adjusted by varying R_x and R_y .

The required values of R_x and R_y for any desired transfer constant θ_{max} may be found as follows: The maximum loss, in nepers, is substituted for θ_{max} in Equation 6 and the equation solved for a . Then the value of R_x is found from Equation 7 and the corresponding value of R_y is found from Equation 5.

What is claimed is:

1. A wave transmission network comprising two T 's connected in parallel, a variable resistance bridging said T 's and a second variable resistance connected in common with the shunt branches of said T 's, one of said T 's comprising two series resistances and an interposed shunt reactance, the other of said T 's comprising two series reactances and an interposed shunt resistance of value R_2 , said reactances being of the same sign, the resistances and reactances comprising said T 's being proportioned to provide maximum transmission loss at a preassigned frequency, and the product of said variable resistances, at every pair of settings, being approximately equal to

$$\frac{2R_1^2R_2}{R_1+2R_2}$$

where R_1 is the value of one of the resistances in said one T .

2. A network in accordance with claim 1 in which each of said reactances is constituted by a capacitance.

3. A network in accordance with claim 1 in which said variable resistances are under a unitary control.

4. A network in accordance with claim 1 in which each reactance in said other T is approximately equal to four times the reactance in said one T multiplied by the ratio of R_2 to one of the resistances in said one T .

5. A network in accordance with claim 1 in which each of said reactances is constituted by a capacitance and the capacitance in said one T is approximately equal to four times one of the capacitances in said other T multiplied by the ratio of R_2 to one of the resistances in said one T .

6. A network in accordance with claim 1 in which said resistances in said one T are equal.

7. A wave transmission network comprising two symmetrical T 's connected in parallel, a variable resistance bridging said T 's and a second variable resistance connected in common with the shunt branches of said T 's, one of said T 's comprising two series resistances each of value R_1 and an interposed shunt reactance, the other of said T 's comprising two equal series reactances and an interposed shunt resistance of value R_2 , said reactances being of the same sign, the resistances

and reactances comprising said T 's being proportioned to provide maximum transmission loss at a preassigned frequency, and the product of said variable resistances, at every pair of settings, being approximately equal to

$$\frac{2R_1^2R_2}{R_1+2R_2}$$

8. A network in accordance with claim 7 in which each of said reactances is constituted by a capacitance.

9. A network in accordance with claim 7 in which said variable resistances are under a unitary control.

10. A network in accordance with claim 7 in which each reactance in said other T is approximately equal to four times the reactance in said one T multiplied by the ratio of R_2 to R_1 .

11. A network in accordance with claim 7 in which each of said reactances is constituted by a capacitance and the capacitance in said one T is approximately equal to four times one of the capacitances in said other T multiplied by the ratio of R_2 to R_1 .

12. A wave transmission network comprising two symmetrical T 's connected in parallel, a first resistance bridging said T 's and a second resistance connected in common with the shunt branches of said T 's, one of said T 's comprising two series resistances each of value R_1 and an interposed shunt reactance, the other of said T 's comprising two equal series reactances and an interposed shunt resistance of value R_2 , said reactances being of the same sign, the resistances and reactances comprising said T 's being proportioned to provide maximum transmission loss at a preassigned frequency, and the product of said first and second resistances being approximately equal to

$$\frac{2R_1^2R_2}{R_1+2R_2}$$

13. A network in accordance with claim 12 in which each of said reactances is constituted by a capacitance.

14. A network in accordance with claim 12 in which each reactance in said other T is approximately equal to four times the reactance in said one T multiplied by the ratio of R_2 to R_1 .

15. A network in accordance with claim 12 in which each of said reactances is constituted by a capacitance and the capacitance in said one T is approximately equal to four times one of the capacitances in said other T multiplied by the ratio of R_2 to R_1 .
